UNITED STATES PATENT OFFICE.

MAX AMS, OF NEW YORK, N. Y.

SHEET-METAL CAN.

SPECIFICATION forming part of Letters Patent No. 678,091, dated July 9, 1901.

Application filed December 28, 1900. Serial No. 41,307. (No model.)

To all whom it may concern:

Be it known that I, MAX AMS, a citizen of the United States, and a resident of New York city, county and State of New York, 5 have invented certain new and useful Improvements in Sheet-Metal Cans, of which the following is a specification.

This invention relates to an improved sheet-metal can and more particularly to effective 10 means for rapidly opening the cover.

In the accompanying drawings, Figure 1 is a top view of an oblong sheet-metal can provided with my improvement. Fig. 2 is a section on line 2 2, Fig. 1; Fig. 3, a section on 15 line 3 3, Fig. 1; Fig. 4, an enlarged section through a portion of the head before it is flanged, and Fig. 5 a top view of a round can provided with my improvement.

The letter *a* represents a sheet-metal can, 20 and *b* is its countersunk cover, connected thereto by means of a lap-joint which projects above the surface of the cover to form a flange *b'*. Within this flange and parallel thereto I provide the top of the cover with 25 two or more concentric weakened circumferential lines. The drawings show three such lines *c c' c''*, each composed of spaced indentations, the indentations of one line being staggered with those of the adjoining line or 30 lines. I have found that by this particular arrangement the cover may be readily torn open, because when for any reason it refuses to be torn on the outermost line *c* the tear

will be transferred to the second line *c'* and thence to the innermost line *c''*.

Within the cover *b* I form a diagonal or chord-like slit *b''*, into which is introduced the inner end of a tongue *d*, which is soldered to the outer side of the cover along the slit. The slit *b''*, as well as the tongue *d*, extends 40 across a corner, Fig. 1, or segment, Fig. 5, of the cover and connects diagonally two different parts of the outermost weakened line *c*.

When the outer end of the tongue is grasped by a suitable key and rolled up, the main 45 body of the cover will become detached along the weakened line or lines, the tearing off of the cover taking place simultaneously around the right and left, along the flange *b'*, so that the cover becomes detached in a quick and 50 effective manner.

What I claim is—

A sheet-metal can having a head provided with a number of concentric weakened lines formed of spaced and staggered indentations, 55 combined with a tongue extending across the outermost weakened line, substantially as specified.

Signed by me at New York city, county and State of New York, this 27th day of December, 1900.

MAX AMS.
